JESSE G. GILMORE, OF PINE BLUFF, ARKANSAS.

PIPE-WRENCH.

1,213,351.

Specification of Letters Patent. Patented Jan. 23, 1917.

Application filed April 15, 1916. Serial No. 91,420.

To all whom it may concern:

Be it known that I, JESSE G. GILMORE, a citizen of the United States, residing at Pine Bluff, in the county of Jefferson and State of Arkansas, have invented certain new and useful Improvements in Pipe-Wrenches, of which the following is a specification.

An object of my invention is to provide a pipe wrench having a pair of jaws, one of which is movable, together with a handle which may be manipulated to tighten the movable jaw to the proper operative relation and subsequent to the tightening operation may be used to swing the wrench to turn the pipe.

A further object is to so construct the parts that when an adjustment of the movable jaw has been obtained, this adjustment will be retained until certain of the parts of the mechanism are manually released, but at the same time, slight play of the parts is permitted to allow the jaw to be slightly released in turning the wrench in the reverse direction, thus permitting the wrench to slide around the pipe in a reverse direction and obviating the necessity of providing ratchets.

With the above and other objects in view, my invention consists in certain novel features of construction and combinations of parts which will be hereinafter set forth in connection with the drawings and then more particularly pointed out in the claims.

In the drawings:—Figure 1 is a view in side elevation with portions of the main jaw broken away to more clearly illustrate the parts of the structure. Fig. 2 is a view in front elevation of the wrench. Fig. 3 is a vertical sectional view taken on the line 3—3 of Fig. 1. Fig. 4 is a fragmentary side elevational view taken from the opposite side from that shown in Fig. 1.

The main jaw member 1 is preferably composed of two side portions 2 and 3, which are shaped to form the gripping jaw 4 and are then sufficiently separated in their remaining portions to provide the case 5.

The movable jaw member 6 has the extension rack bar 7 thereof shaped to be received between the side portions 2 and 3 and within the casing 5, and the gripping jaw is formed in the hook-shaped extension 8 which has the end thereof roughened or toothed as at 9, it being also understood that the jaw portion 4 is likewise provided with

the teeth 10. The inner edge of the extension rack bar 7 is made smooth and the friction bearing rolls 11 are mounted in the casing 5 to have this smooth edge bear and move thereon as the extension rack bar may be moved into or withdrawn from the case, and the outer edge of this extension rack bar has the rack teeth 12 formed thereon.

A handle 13 is bifurcated at its inner end to be fitted over the side portions 2 and 3 and at its bifurcated end is pivotally connected with the gripping jaw through the medium of the rivet or pin 14. This handle 13 has a tongue extension 15 disposed between the arms thereof within the bifurcated portion, and the side portions 2 and 3 are spaced sufficiently apart that this tongue extension 15 can have free sliding movement therethrough as the handle is swung around its pivotal mounting on the pin 14.

A toothed wheel 16 is mounted by the pin 17 in a relation to have the teeth thereof mesh with the teeth of the rack 12, this wheel 16 being spaced sufficiently from the friction rolls 11 that the extension rack bar 7 may have free movement longitudinally but is held against side play, and a second toothed wheel 18 is pivotally mounted between the side portions to form a bearing 85 for the rack bar 7 at a point spaced from the mounting of the wheel 16. The toothed wheels 16 and 18 and the bearing rolls 11 form the guideway for the extension rack bar 7 which is held against lateral displacement through the bearing engagement with the side portions 2 and 3, and as the extension rack bar 7 is moved into or extended from the casing 5, the proximity of the toothed portions 9 and 10 of the jaws is 90 varied.

The tongue 15 is widened out to form the arcuated rack 19, this rack being curved on the arc of a circle having the pivot pin 14 as its center, and being so disposed that 100 when the parts are assembled the teeth of the rack mesh with the teeth of the wheel 16. By arranging the parts as set forth, when the handle 13 is moved, as to the right in Fig. 1, the engagement of the teeth of 105 the rack 19 with the toothed wheel 16 will cause this wheel to be turned in a direction to draw the extension rack bar 7 farther into the casing 5, and in consequence, the toothed gripping portion 9 will be brought into 110 closer proximity to the toothed gripping portion 10.

The edges of the side portions 2 and 3 between which the tongue extension 15 works are curved around the pivot pin 14 as a center and the teeth 20 are provided on the side member 2 to form a segmental ratchet rack, the spring catch 21 being provided on the handle 13 to engage with these teeth to hold the handle against return movement, and this spring catch being provided with a handle or knob 22 which may be grasped and moved to release the spring catch. The side portion 3 has the teeth 23 provided on the curved edge thereof and faced in a direction opposite to the facing 15 of the teeth 20, and a spring catch member 24 is carried by the handle to engage with these teeth, the handle or knob 25 being provided to be moved to release the spring catch 24.

20 An indicating scale or measure 26 is located on one side of the casing 5, and has indications marked thereon to show various widths of setting of the movable jaw with respect to the fixed jaw so that the wrench 25 may be set to take various sizes of pipe. An opening 27 is provided through the case 5 in the forward edge adjacent the toothed periphery of the wheel 18. If desired the curved hook of the member 6 may have the 30 teeth 28 provided therein and the teeth may be provided at 29 on the members comprising the case 5 so that smaller pipes than those of a dimension to be gripped between the toothed faces 9 and 10 may be held and 35 turned by the use of the wrench.

In the use of the device, the wrench will be fitted with the toothed face 10 in bearing engagement on the pipe and then with the spring catch 24 released the handle 13 may 40 be swung forwardly to the proper extent that the toothed face 9 is in proper bearing against the pipe, the spring catch 21 following the handle over the teeth 20 and acting to engage with the face of one of these 45 teeth to hold the handle against accidental displacement or against return movement without first releasing the spring catch 21. With the parts in this relation, the catch 24 will be released to catch in one of the teeth 50 23 and the handle 13 may then be swung in either direction and the pipe will be held between the toothed faces 9 and 10, and will be turned, or if this pipe be fitted between the toothed portions at 28 and 29, these teeth 55 will grip the pipe and cause the same to be turned.

When the wrench is being used in a close place, the handle may be swung back so that the spring catch will be brought into 60 bearing abutment against the face of the adjacent tooth 20 and this will give sufficient play that the movable jaw 6 will be slightly released from the pipe and the proper loose turning movement can be accomplished, 65 after which the pressure again exerted on

the handle 13 will cause the jaw 6 to be again tightened to the working position and in consequence a new grip is obtained on the pipe and further turning movement may be transmitted thereto.

The reason for providing the orifice or opening 27 is that on some occasions it may be desired to set and hold the movable jaw 6 in a fixed relation, and under such circumstances, a small rod or pin may be inserted through this opening in the relation shown by the dotted lines and through engagement with the teeth of the wheel 18, this rod or pin will hold the wheel against turning movement and in consequence will 70 lock the extension rack bar 7 against movement in either direction. As either spring catch 21 or 24 is released, the handle 13 may have swinging movement in one direction or the other, and when both catches are released, the handle may be freely swung in either direction, it being understood that any swinging movement of the handle 13 will cause the teeth of the arcuated rack 19 to transmit movement to the toothed wheel 80 16 and in consequence to the extension rack bar 7.

While I have herein shown and described only one specific form of my invention, it will be understood that the member 1 might 95 be constructed of two portions arranged in a varied manner, that the arcuated rack might be disposed in a varied relation with the remaining parts, and that other changes and modifications might be resorted to in 100 the form and arrangement of the several parts without departing from the spirit and scope of my invention, and hence I do not wish to be limited to the exact disclosure but only to such points as may be set forth 105 in the appended claims.

I claim:

1. A wrench comprising a fixed jaw member having a casing formed as a part thereof, an adjustable jaw member having an extension bar mounted to be capable of movement into and extension from said case, a handle pivotally mounted on the fixed jaw member, means to be actuated upon swinging of the handle to move said movable jaw 110 to its adjusted position, and means to hold the handle in a fixed relation to retain the setting of the movable jaw.

2. A wrench comprising a jaw member having a case formed as a part thereof, an adjustable jaw member having an extension rack bar formed as a part thereof, and received in said case to be capable of endwise movement, a toothed wheel mounted in the case with the teeth thereof in engagement 115 with the teeth of the extension rack bar, means to turn said toothed wheel to cause movement of the adjustable jaw to the proper relation, and means carried by the means arranged to turn said toothed wheel 130.

- and arranged to hold said means against displacement when the proper adjustment of the movable jaw has been attained.
3. A wrench comprising a jaw having a case formed as a part thereof, a movable jaw provided with an extension rack bar mounted in said case to be capable of end-wise movement, a toothed wheel mounted in the case with the teeth thereof in engagement with the teeth of the extension rack bar, a handle pivotally mounted on the case, and an arcuated rack carried by said handle in engagement with the teeth of the wheel in such relation that as the handle is swung the wheel is turned to cause movement of the extension rack bar and in consequence adjustment of the adjustable jaw.
4. A wrench comprising a fixed jaw, an adjustable jaw having an extension rack bar formed as a part thereof, friction rolls with which said rack bar has engagement, toothed wheels mounted on the fixed jaw with the teeth thereof in engagement with the teeth of the rack bar, a handle pivotally mounted on said fixed jaw, an arcuated rack carried by said handle with the teeth thereof in engagement with the teeth of one of said wheels, said parts being so arranged that as the handle is swung the toothed wheel is turned to cause movement of the extension rack bar and consequently of the adjustable jaw, means to indicate by the relative positioning of the handle the width of extension of the jaws, and means to hold the handle in the adjusted relation to maintain the fixed adjustment of the jaw.
5. A wrench comprising a fixed jaw, an adjustable jaw having an extension rack bar formed as a part thereof, friction rolls with which said rack bar has engagement, toothed wheels mounted on the fixed jaw with the teeth thereof in engagement with the teeth of the rack bar, a handle pivotally mounted on said fixed jaw, an arcuated rack carried by said handle with the teeth thereof in engagement with the teeth of one of said wheels, said parts being so arranged that as the handle is swung the toothed wheel is turned to cause movement of the extension rack bar and consequently of the adjustable jaw, and means to hold the parts in the proper adjusted relation.
6. A wrench comprising a fixed jaw, an adjustable jaw having an extension rack bar formed as a part thereof, friction rolls with which said rack bar has engagement, toothed wheels mounted on the fixed jaw with the teeth thereof in engagement with the teeth of the rack bar, a handle pivotally mounted on said fixed jaw, an arcuated rack carried by said handle with the teeth thereof in engagement with the teeth of one of said wheels, said parts being so arranged that as the handle is swung the toothed wheel is turned to cause movement of the extension rack bar and consequently of the adjustable jaw, means to indicate by the relative positioning of the handle the width of extension of the jaws, and means to hold the handle in the adjusted relation to maintain the fixed adjustment of the jaw.

In testimony whereof I affix my signature in presence of two witnesses.

JESSE G. GILMORE.
